Atty.

UNITED STATES PATENT OFFICE.

LEE S. CHADWICK, OF SHAKER HEIGHTS, OHIO, ASSIGNOR TO THE CLEVELAND METAL PRODUCTS COMPANY, OF CLEVELAND, OHIO, A CORPORATION OF OHIO.

AIR-CONTROLLING MEMBER FOR OIL BURNERS.

Application filed June 29, 1922. Serial No. 571,671.

To all whom it may concern:

Be it known that I, LEE S. CHADWICK, a citizen of the United States, residing at Shaker Heights village, in the county of 5 Cuyahoga and State of Ohio, have invented a certain new and useful Improvement in Air-Controlling Members for Oil Burners, of which the following is a full, clear, and exact description, reference being had to 10 the accompanying drawings.

This invention relates to oil burners, and more particularly to an improved air controlling member or so-called flame spreader for use with burners of this class.

15 Devices similar to that constituting the subject matter of this application are shown in my former applications Serial Nos. 528, 813, 528,814, 528,833 (the last mentioned being a joint application of myself and one 20 Marc Resek) filed January 12, 1922, 541,898, filed March 8, 1922, 546,349, filed March 24, 1922, and in an application filed concurrently herewith, and entitled "Air distributor for liquid fuel burners."

25 The general object of my present invention is to provide an improved air controlling member or flame spreader that renders the burner wherewith it is used more powerful and efficient.

30 Another object is to provide a novel construction for an air controlling member or flame spreader which insures the accuracy so essential to the successful functioning of devices of this character.

35 A further object is to provide a construction facilitating assembly, expediting manufacture, and increasing the strength and durability of the device.

These objects, with others hereinafter appearing, are attained in the embodiment of 40 the invention illustrated in the accompanying drawing and defined in the claims annexed hereto.

In the drawing Fig. 1 represents a central vertical section through the upper portion of an oil burner and through my improved air controlling member or flame spreader wherewith the burner is equipped; Fig. 2 is a sectional plan substantially on the line 2-2 of Fig. 1; and Fig. 3 is a section through the burner and air controlling member in a horizontal plane as indicated by the line 3-3 of Fig. 1, one side of the air controlling member being omitted to

better reveal the spanner or supporting element therefor. 55

The oil burner is of the usual tubular form and includes inner and outer wick tubes 1 and 2, respectively, between which a cylindrical wick 3 is guided, the wick being adapted to be raised and lowered by wick raising means (not shown). A spanner 5 which, in the present instance, consists of an annulus having a downwardly opening channel cross section, is situated 60 within the upper end of the inner wick tube and is spaced a suitable distance downwardly from the top thereof. This spanner constitutes a support for the air controlling member or flame spreader. A frame 6 depends from the spanner, and pivotally connected to the frame in the zone of the spanner are locking elements 7 which are restrained against undue pivotal movement by stops 8 that extend from the upper end of 65 the frame 6 through openings 9 in the locking elements. The locking elements have keeper portions 7a.

As I shall more fully explain hereinafter, and as disclosed and claimed in the aforesaid application No. 528,833, the locking elements cooperate with the air controlling member in such manner as to secure it to the spanner; and the spanner and frame 6 are adapted to be lifted, through the intervention of the air controlling member, by the wick, for the purpose of setting into 80 operation certain wick stop mechanism carried by the frame and cooperating with the wick raising means, as fully disclosed in 85 my hereinbefore mentioned application No. 528,813. The movement of the spanner and the latching thereto of the flame spreader, however, have nothing to do with my present invention and are included in the present disclosure only because the preferred 90 embodiment of my invention is designed for cooperation therewith.

The air controlling member or flame spreader comprises a central tubular element 10, which by reason of its function I shall hereinafter refer to as the lock. This lock is made up of an upper section 11 and a lower section 12 that are drawn from sheet metal, the former section being closed at its upper end by an integral wall 13 and being flared at its lower end in two steps, the lower of which constitutes 100 105

a shoulder 14 from the outer edge of which depends a flange 15. The upper end of the lower section 12 is flared outwardly to form a horizontally disposed abutment 16, and 5 then upwardly to form a flange 17 which fits within the former flange 15 and below which the edge portion of the latter flange is crimped to clamp the parts firmly together with the edge of flange 17 against the 10 shoulder 14.

The body of the air controlling member or flame spreader is designated 20 and it is made up of a cylindrical wall 21 that terminates at its upper end in a converging portion 22 and joins at its lower end, through a beaded depression 23, a gradually downwardly and inwardly inclined bottom 24 that terminates in a flange 25 which fits about the lower end of the section 12 of the 15 lock 10 and is secured thereto, preferably by a series of indentations 26. It will be noted that the body, comprised of the foregoing parts, is constructed of an integral piece of sheet metal and this insures the body being 20 absolutely true and round and provides the accuracy which is so necessary to the satisfactory operation of devices of this character. By being so constructed, there is little liability of the body ever becoming deformed through ordinary use and 25 handling.

30 indicates what is usually referred to as the flange of the flame spreader and throughout its outer edge portion it is 35 bulged upwardly as shown at 31 and beyond this bulged portion it extends abruptly downwardly and terminates in a substantially vertical lip 32 that is disposed above the upper end of the wick. It is found that, 40 by forming the flange 30 with its edge substantially vertical, as described the efficiency and power of the burner is considerably increased and the character of the flame is improved. The flange has a central sleeve portion 33 which is snugly engaged about the enlarged lower end of the upper section 11 of the lock 10 and bears upon the exterior of the shoulder 14. The flange may 45 be secured to the lock by any suitable means, 50 as by a series of indentations 34.

Fitting down over the upper end of the lock is the downwardly and outwardly inclined top 36. The top may be secured to the lock by a series of indentations 37, and 55 spaced inwardly a suitable distance from its edge are lugs 38 that are struck from the material of the top and bear upon the bulged portion of the flange 30 so as to maintain an accurate spacing of these parts 60 and provide between them a restricted air passage. In the horizontal plane of this air passage, the upper section of the lock 10 is provided with segmental openings 40, the supporting bars which separate them being 65 designated 41.

The reduced upper end of a locking pin 45 is guided through a central aperture in the top wall 13 of the lock 10 and through an aligning aperture in a guide member 46 which depends from said top, the pin being equipped above the spreader with a knob 47. When the pin is depressed or allowed to drop of its own weight its tapered lower end 48 enters between the locking elements 7 and spreads them apart thereby to engage 70 their keeper portions 7^a with the abutment 16 of the lock to latch the flame spreader to the spanner 5. When it is desired to release the flame spreader and lift it from the burner, the knob of the pin is grasped and the spreader lifted through the intervention of the pin, the initial upward movement of the pin in advance of the spreader causing its lower end to be withdrawn from between the locking elements, allowing them to swing 80 inwardly out of engagement with the abutment 16, the spreader moving with the pin upon contact of the enlarged end of the pin with the guide member 46.

The top wall 13 of the upper section of 90 the lock 10 is provided with openings 50; the spreader top 36, with openings 51; the bottom 24 of the body 20, with openings 52, while the cylindrical wall 21 of said body has a series of relatively small openings 53, 95 and the converging portion 22 thereof, a series of similar openings 54.

As the parts are illustrated in Fig. 1, the wick 3 is in "high" position. It may be 100 adjusted to any position between this and its lowermost burning position (which is somewhat below the upper ends of the wick tubes) without the position of the flame spreader being altered. In the type of 105 burner shown, which is the one incorporating the automatic wick stop mechanism covered by my previously mentioned application No. 528,813, the flame spreader descends when the wick has passed its lowermost burning position in a downwardly direction and finally comes to rest with its 110 flange 30 engaging the top of the wick. This is of no consequence, however, in the present case, and the flame spreader may be considered as supported at the elevation 115 shown while the wick occupies any adjusted position within its burning range. Assuming then that the burner is lighted with the parts in the position shown in Fig. 1, or with the wick adjusted to a lower position, 120 a flow of air is induced by the heat upwardly through the burner, the major portion of the air rising through the lock 10 and escaping through the openings 40 and through the restricted passageway between the bulged portion 31 of the flange 30 and the outer edge portion of the top 36.

At this point it may be explained that the air which is divided into substantially radial streams by the supporting bars 41 that sepa- 125 130

rate the openings 40 is spread out horizontally as it continues through the aforesaid restricted passageway and consequently the voids produced by said bars are filled in and 5 the air issues from beneath the top 36 in an unbroken and continuous sheet. This jacket of air, so to speak, protects the parts of the spreader which it encloses from the intense heat of the flame. A part of the air, however, which passes through the openings 40 10 escapes through the openings 51 of the top 36, preventing that part passing upwardly about the edge of the top from flowing in over the top of the spreader. As a result, 15 all the air rises in a substantially vertical column through a drum which surmounts the burner, the use of drums or flues with burners of this character being well understood by those acquainted with the art, 20 wherefore its showing in this connection is deemed unnecessary. For a complete disclosure of such a burner, reference may be had to Letters Patent No. 848,828, issued April 2, 1907 to W. R. Jeavons. A limited 25 amount of air also passes through the perforations 50 of the top wall 13 of the lock and retains the knob 47 at a comparatively low temperature.

The remainder of the air rising through 30 the burner passes upwardly through the openings 52 in the bottom 24 of the body 20 and through the slight annular passageway between the spanner 5 and the inner wick tube 1. The air rising through the 35 openings 52 is deflected outwardly along the cylindrical wall of the body 20 by the horizontal portion 16 of the lower section of the lock 10 and the greater amount of this air flows over the upper edge of the body and 40 out from beneath the flange 30 and supplies the flame with the oxygen required to promote combustion at the same time imparting proper shape to the flame. A limited amount of air is supplied to the space between the 45 upper end of the body and the adjacent portion of the wick through the perforations 53 and 54 and through the passageway between the spanner and the inner wick tube. The air passing through this space 50 prevents vapors from descending thereto and avoids the condensation of vapors within this region.

I previously explained how the air issuing through the openings 40 and divided 55 into radial streams by the bars 41 is subsequently thinned out and reunited into a continuous horizontal sheet by the peripheral portions of the flange 30 and the top 36 between which it flows; and in this connection I may further explain that inasmuch as the lugs 38 which accurately space these elements apart are radially disposed and are comparatively thin they do not have the effect of breaking up this sheet of air into 60 separate streams beyond this point and of

causing streaks in the flame. While this method of handling the air is highly essential to the successful operation of the present air controlling member or spreader, it is developed to a higher degree in the type of 70 device which constitutes the subject matter of the application which I am filing concurrently herewith and accordingly claims on this feature are made in the other application.

Having thus described my invention, what I claim is:

1. In an air controlling member of the character set forth, the combination of a tubular central element having a circumferential enlargement spaced upwardly a suitable distance from its lower end, a flange surrounding said element above said enlargement, the flange having an annular horizontal portion which joins at its inner 80 edge a sleeve that fits about and is secured to said enlargement and which joins at its outer edge an upwardly bulged portion that terminates at its outer edge in a substantially vertical depending lip, a top surrounding and secured to the central element above and in properly spaced relation to the flange, and a body surrounding the lower portion of said element and comprising a cylindrical wall spaced outwardly from the aforesaid 85 enlargement and joining at its lower edge a bottom wall that is secured to the lower end of the central element, said bottom wall being provided with air openings.

2. In an air controlling member of the character set forth, the combination of a central tubular member having a stepped circumferential enlargement spaced a suitable distance above its lower end, the stepped enlargement providing an upwardly facing 100 shoulder at the base of a cylindrical portion, a flange surrounding said element and extending outwardly therefrom and having at its inner edge a depending sleeve which fits about and is secured to the said cylindrical portion with its lower edge abutting said shoulder, a top applied to and surrounding the central element above and in properly spaced relation to the flange, and a body surrounding the lower portion of said central element and comprising a cylindrical wall terminating at its upper end a suitable 105 distance below the flange and joining at its lower end a bottom wall that is secured to the lower end of the central element, said 110 bottom wall having air openings.

3. In an oil burner, the combination of inner and outer wick tubes, a wick therebetween, and an air controlling member situated within the upper end of the inner wick tube, said member comprising a central tubular element, a body surrounding the lower end of said element and consisting of a cylindrical wall in close proximity to the inner wick tube and a bottom extending inwardly 115 120 125 130

from said wall and joining the lower end of the element, and a flange extending outwardly from the central element above the wick tubes, said flange having a downwardly projecting substantially cylindrical edge portion in opposed relation to the top of the wick.

4. In an oil burner, the combination of inner and outer wick tubes, a wick therebetween, an annular support extending about the interior of the inner wick tube and spaced below its upper end, and an air controlling member situated within the upper end of the inner wick tube, said member comprising a central tubular element, a one-piece body consisting of a cylindrical wall in close proximity to the inner wick tube and a perforate bottom extending inwardly from said wall and joining the lower end of the central element, the body being formed with a depressed bead where its cylindrical wall joins said bottom, said bead resting upon the aforesaid support, and a flange extending outwardly from the central element above the wick tubes.

5. In an oil burner, the combination of inner and outer wick tubes, a wick therebetween, and an air controlling member situated within the upper end of the inner wick tube, said member comprising a central tubular element having a closed top and open bottom, a body surrounding the lower end of said element and consisting of a cylindrical wall in close proximity to the inner

wick tube and a bottom extending inwardly from said wall and joining the lower end of said element, an annular flange having its inner edge formed to provide a sleeve which encircles and is attached to the central element, said flange projecting outwardly over the wick, an annular top having its inner edge formed to provide a sleeve which surrounds and is attached to the central element, said top being spaced above the flange, the central element having air openings between the top and flange and extending a substantial distance above said top.

6. An air distributor for liquid fuel burners of the character set forth comprising a tubular supporting member, two substantially horizontal flange-like elements surrounding the exterior of the supporting member, one above the other, the latter constituting the flame spreader flange, said elements converging outwardly to provide a restricted passageway, and a flame spreader body surrounding the supporting member below the aforesaid elements and in spaced relation to the lower one thereof, the tubular supporting member having a circumferentially disposed series of openings that are separated by supporting parts and are located between the horizontal planes of the aforesaid flange-like elements.

In testimony whereof, I hereunto affix my signature.

LEE S. CHADWICK.
